Henry Wilson

UNITED STATES PATENT OFFICE

HENRY WILSON, OF BINGHAMTON, NEW YORK.

SKELETON SKATES.

Specification forming part of Letters Patent No. 40,530, dated November 3, 1863.

To all whom it may concern:

Be it known that I, HENRY WILSON, of Binghamton, in the county of Broome and State of New York, have invented a new and useful Improvement in Skeleton Skates—that is, such skates as may be secured to the foot without the addition of straps or similar fastenings; and I do hereby declare that the following is a full, clear, and exact description of the construction and operation of the same, reference being had to the annexed photograph, making a part of this specification, and to the letters of reference marked thereof.

A represents a skate bar or iron, armed at the inner side of the backward end with one or more points, or their equivalent, for reacting against the springs B B, and also for securing the heel of the boot or shoe to its position on the plate C, the one extremity of the springs B B being secured to the heel-post G, and the other to the cramp D, which is free to move back and forth on the forward part of the skate bar or iron, by means of the box E on the under side of said cramp D.

In case foreign substances should deface the ice, and the skater's sudden contact with them further distend the springs, the point of the hook F may be brought in contact with the inner side of the heel of the boot or shoe, and compelled to penetrate it by turning a thumb-nut on the other end of the hook, the pressure of the nut acting against the back-

ward part of the skate-bar or heel-post, which the screw end of the hook pierces.

Operation: The boot or shoe of the skater being wedge-shaped, or widening from the toe toward the ball, we will readily see that this skate may be firmly secured to his boot or shoe by inserting the toe between the curls of the cramp, described above, and distending the springs by drawing the skate backward until the point or points shall pass the heel, and by the action of the springs penetrate it on the backward side. Further security to the heel may be had by bringing the point of the hook F in contact with the inner side of the heel of the boot or shoe, and turning the thumb-nut, as described above. The same skates may be used on several sizes of boots or shoes, as the position of the cramp is determined by the width of the boot or shoe.

I claim—

1. The cramp D, combined with springs and points, as described above, and for the purposes set forth herein.
2. The hook, with its screw and thumb-nut, or their equivalent, for assisting the springs in securing the whole to the foot, as above described.

HENRY WILSON.
